UNITED STATES PATENT OFFICE.

CHARLES A. LEE, OF HERKIMER, NEW YORK.

FOOT-REST.

SPECIFICATION forming part of Letters Patent No. 470,688, dated March 15, 1892.

Application filed March 23, 1891. Serial No. 386,165. (No model.)

To all whom it may concern:

Be it known that I, CHARLES A. LEE, of Herkimer, in the county of Herkimer and State of New York, have invented certain new and useful Improvements in Foot-Rests; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to an improvement in foot- rests, and more particularly to those adapted to use with platform-rockers.

In the drawings which accompany and form part of this specification, and in which similar numerals of reference refer to corresponding parts in the several views, Figure 1 shows a side view of my foot-rest in connection with a platform rocking-chair. Fig. 2 shows the foot-rest fully extended in connection with the platform of the chair. Fig. 3 shows a top view of the foot-rest extended and the platform. Fig. 4 shows the same parts folded. Figs. 5, 6, 7, and 8 show details of the mechanism of the foot-rest.

Referring more specifically to the reference-numerals marked on the drawings, 1 indicates the platform rocking-chair mounted on platform 2 in the usual manner. Extending from front to back in the center of the platform and secured therein is rod or way 3, on which runs eye 4, connected with the foot-rest frame 5. Foot-rest frame 5 may rest and run on round 6 of the platform, and is supported at its forward or projecting end by legs 7. Pivoted at 8 in the foot-rest frame 5, on either side, is a pair of arms 9. To the free ends of the arms 9 are pivoted at 10 arms 11, to the free end of which arms 11 is hinged at 13 foot-rest cushion 12 in such manner that it will swing with reference to the arm from the position shown in Fig. 6 to that shown in Figs. 4 or 7. The free ends 45 of arms 9 9 are connected by a cross-bar 14. To the under side of the arms 9 9 is secured by clasps 15 15 an adjustable supporter 16, having ratcheted arms 17. The ratchet-teeth of arms 17 are adapted to engage on pins 18, secured in the frame 5. Spanning the corner of the frame 5 are supporting-braces 19, adapted to support the free ends of swinging arms 9 9

when in their lower position, together with the several connecting parts. The cushion-stool is of a length greater than the width of frame 5, so that when in its folded position it will engage on and be supported by the side rails of frame 5. 55

The foot-rest may be folded and slid out of the way beneath the seat of the chair, as shown in Fig. 4, and when in use may be withdrawn until the eye 4 engages against the front round of the platform, and the cushion-stool may be used immediately in front of the chair in the position shown in Fig. 7, or partially extended, 65 as shown in Fig. 1, or fully extended, as shown in Fig. 2.

In the position shown in Figs. 2 and 6 the stool 12 is supported by arms 11 engaging against cross-piece 14, and the height of the stool 12 may be regulated by engaging the ratcheted arms 17 of the supporter 16 with fixed pin 18. In the folded position the free ends of the arms 9 are supported upon braces 19 19, and the supporting-arms 16 are also 75 supported or held up close to the under side of arms 9 by resting on the braces 19, the rest being connected by the eye 4 to the rod 3 of the platform, and the eye 4, being large in size with reference to rod 3, permits the foot-rest 80 to be swung to either side, so that a person could readily get into or out of the chair without inconvenience from the foot-rest or foot-rest frame. It will also be observed that the cushion-stool 12 might be used supported on 85 the arms 9 and while in their elevated position, which brings the stool closer to the front of the chair and gives numerous adjustments of the foot-rest stool to the chair.

What I claim as new, and desire to secure 90 by Letters Patent, is—

1. The combination, with the platform 2 of a rocker having a single central rod 3 extending from front to rear of platform, of a foot-rest frame 5, connected to the rod 3 by eye 4 95 and supported thereon and on round 6 at its rear end and supported at its front end by legs, swinging arms 9, pivoted at their inner ends to the frame 5 and having a cross-bar 14 at their outer ends, arms 11, pivoted to the 100 swinging ends of the arms 9 and adapted to turn on their pivots so that the arm 11 engages against the cross-bar 14, supporting the arm 11 in an upright position, the stool or

cushion 12, hinged at 13 to the free ends of the arms 11 to swing from a horizontal folded position on the frame 5 to its open position supported on the ends of arm 11, and an adjustable supporter 16 for the arms 9, substantially as set forth.

2. The combination, with the platform 2 of a rocker having a single central rod 3 extending from front to rear of platform, of a foot-rest frame 5, connected to the rod 3 by eye 4 and supported at its front end by legs and having braces 19 spanning the outer corners of the frame and being at the lower side of the frame to act as supports, swinging arms 9, pivoted at their inner ends to the frame 5

and having a cross-bar 14 at their outer ends, arms 11, pivoted to the free end of the arms 9 and adapted to turn on their pivots so that the arm 11 engages against the cross-bar 14, supporting the arms in upright position, the 20 stool or cushion 12, hinged at 13 to the free end of the arms 11, and an adjustable supporter 16 for the arms 9, substantially as set forth.

In witness whereof I have affixed my signature in presence of two witnesses.

CHAS. A. LEE.
